UNITED STATES PATENT OFFICE.

ANDREW L. RIKER, OF BRIDGEPORT, CONNECTICUT, ASSIGNOR TO THE "LOCOMOBILE" COMPANY OF AMERICA, OF NEW YORK, N. Y., A CORPORATION OF WEST VIRGINIA.

CARBURETER.

1,264,860.

Specification of Letters Patent. Patented Apr. 30, 1913.

Original application filed July 16, 1902, Serial No. 115,841. Divided and this application filed May 31, 1912.
Serial No. 700,704.

To all whom it may concern:

Be it known that I, ANDREW L. RIKER, a citizen of the United States, and a resident of Bridgeport, county of Fairfield, State of Connecticut, have invented an Improvement in Carbureters, of which the following description, in connection with the accompanying drawings, in a specification, like characters on the drawings representing like parts.

10 This invention relates to internal combustion engines and more particularly to means for providing a mixture of hot and cold air for the fuel supply of the engine as well as to means for regulating the proportions of such mixture. This application is a division of my prior co-pending application, Serial No. 115,841, filed July 16, 1902 and patented August 22, 1916, No. 1,195,399. The invention will be best understood by reference to the following description when taken in connection with the accompanying illustration of one specific embodiment thereof, while its scope will be more particularly pointed out in the appended claims.

25 In the drawings:

Figure 1 is a top or plan view of the forward portion of a motor vehicle equipped with an internal combustion engine embodying one form of the invention;

30 Fig. 2 is a side elevation of the same;

Fig. 3 is a vertical section taken through the fuel and air mixing and regulating device;

35 Fig. 4 is a horizontal section on the line 4—4 in Fig. 3;

Fig. 5 is a vertical longitudinal section of the device for regulating the admission of cooled or warmed air to the mixing devices;

40 Fig. 6 is a vertical cross section on the dotted line 6—6 in Fig. 5; and

Fig. 7 is a perspective detail of a part of Fig. 5 to be referred to.

Referring to the drawings and to the embodiment of my invention there illustrated, I have shown the same applied to a motor vehicle, the fore part only of which is shown. Such a vehicle is provided with wheels 1 carrying a suitable spring-supported body frame 2, the latter sustaining the

engine 3 and operating to drive the vehicle 50 through the clutch 4, transmission shaft 5, and other parts not herein shown. These various elements may be of any suitable or desired type or construction so far as concerns my present invention and require no 55 further or detailed description herein.

The gasoline or other suitable fluid may be conducted through the pipe 6 from any suitable supply tank (not here shown) to the fuel and air mixing and controlling device 60 7 shown in Fig. 1 and illustrated in detail in Fig. 3.

Referring to the latter figure, the fuel supply pipe 6 is shown entering at the lower left-hand portion of the figure where it is 65 connected by suitable coupling with the separator 8 depending from the principal casting 9 in which the various working parts are preferably arranged.

The bottom of the separator 8 is closed by 70 a plug 10 which is provided with a vertical tubular extension 11 flanged outwardly at its top to fit closely the bore of the separator thus to compel fuel from the pipe 6 to pass through the side openings 12 in the said 75 extension to the interior thereof, thence upward through the strainer 13 applied to the upward end of said extension. Any water which may be mixed with the fuel separates therefrom in the separator 8 and may 80 be drawn off through a cock 14 in the bottom thereof. This construction permits a convenient means for removing the strainer 13 whenever necessary for cleaning.

The fuel, after passing through the separator 8, rises through the opening 15 into the float chamber 16 formed within the casting 9. The entrance opening 6 is controlled by a preferably ball valve 17 on the lower end of a valve stem 18 which rises through 85 the float chamber 16 and has threaded upon its upper end a stop guide 19 which guides the valve stem in its vertical movements.

Loosely surrounding the valve stem 18 is the float 20 which rises with the fuel in the 90 said chamber and when the fuel reaches the proper level therein, said float contacting with the bottom of the stop guide 19 on the

valve stem will lift the valve stem and its valve to close the valve opening 15 and cut off further admission of fuel. The level of the fuel in the float chamber may be regulated by threaded adjustment of the stop guide on the valve stem 18 and the valve stem may be manually depressed to admit additional fuel to the float chamber for starting the engine by the depression of the sliding starting device 21 which is vertically slidable in a perforation in the top of the inverted cup 22, and is normally retained in its elevated position by the spring 23.

At or near the bottom of the float chamber 16 is an outlet passage 24 which communicates with an annular chamber 25 surrounding the atomizing nozzle 26 screwed into the bottom of the mixing chamber 27. This atomizing nozzle 26 has a vertical axial passage 28 with which the outlet passage 24 communicates through one or more side openings 29. The atomizing nozzle 26 is provided with an exteriorly tapered upper end which is arranged within and in close proximity to the correspondingly tapered cone 30. This cone is carried by and at the lower end of a throttle cylinder or cylindrical throttle 31 arranged within the mixing chamber 27 and adapted to be rotated therein by means of a stem 32 projecting from its upper end.

Within the cylindrical throttle 31 and surrounding the top of the cone 30 but not covering the opening therein, is a fine mesh gauze 33, and immediately above this gauze or netting is an opposed deflecting cone 34 depending from the top of the cylindrical throttle. The mixing chamber 27 near its lower end and below the level of the gauze 33 is provided with an air inlet 35, and above the level of said gauze 33 is provided with an outlet 36, and immediately opposite these openings 35, 36, the cylindrical throttle 31 is provided with corresponding openings 37, 38, adapted when in proper rotative position, to register with said openings 35, 36.

Rotation of the cylindrical throttle 31 will thus open and close the openings 35, 36, in the side of the mixing chamber, in fact that portion of the opening 35 communicating with the interior of the throttle outside of the cone 30, may be completely cut off by sufficient rotation of the said throttle. The bottom of the cylindrical throttle, however, is above the bottom of the air inlet opening 35, and consequently the admission of air from the said opening below and to the interior of the cone 30 is never cut off whatever be the rotative position of the throttle.

The opening 36 at the upper end of the mixing chamber 27 is connected by a pipe (see Figs. 1 and 2) with the engine 3

whereby the movements of the piston therein, in a manner well understood by those conversant with the art, will create a sufficient vacuum to draw air inward through the inlet 35, thence upward within the cylinder throttle both at the interior 70 and at the exterior of the cone 30 therein. The air thus drawn upward from the interior of the cone 30 issues with considerable force through the contracted ring-like opening 75 surrounding the atomizer nozzle 26 at the upper end of the cone, and thus draws outward from the said nozzle the liquid fuel which is maintained therein at a level with that of the fuel in the float chamber 16, which level preferably is 80 slightly below the top of said atomizer nozzle.

This fuel is thrown with considerable force against the opposing conical surfaces of the baffle cone 34 which scatters and 85 atomizes it and causes it to be thoroughly mixed with the air drawn upward at the exterior of the cone, the combined mixture of fuel and air passing thence forward through the opening 36 to the engine, there 90 to perform its work.

By rotating the cylindrical throttle 31 more or less within the mixing chamber 27, the quantity or volume of mixture permitted to pass to the engine through the opening 95 36, may be regulated or controlled at will, and in the same proportion reduces the amount of air permitted to enter through the inlet opening 35 to the interior of the throttle cylinder outside the cone 30 therein. 100 The admission of air below and to the interior of the cone 30 however, remains always open and free. This insures proper operation of the atomizer at all times regardless of the extent to which the volume 105 of air or mixture required, may be reduced; in other words, as the volume of mixture drawn from the chamber, and air admitted to the chamber is reduced, if the reduction in air admission take place within the cone 110 30 as well as the outside thereof, there would soon come a time when the atomizer would refuse to work because so large a portion of the reduced quantity of air would 115 pass forward outside the cone. This, however, is entirely obviated and the permanency of the atomizing effect is insured by maintaining constant the admission of air through the interior of the cone and by causing the reduction to take place entirely at 120 the exterior thereof where it can exercise no effect upon the atomizer.

As the atomizer draws the fuel from the float chamber 16 and reduces the level of fuel therein, the float drops and opens the valve 17 to admit a further supply of fuel, the action being such that in practice the float maintains the valve open sufficiently

to insure a substantially continuous admission of fuel both to the float chamber and also to the mixing chamber 27.

To start the engine, the starting device 5 21 is depressed, thereby causing the fuel to overflow the top of the atomizer nozzle and spread it upon the fine gauze 33 in the form of a thin film.

In warm weather the engine will operate 10 successfully with the use of cold or atmospheric air drawn into the mixing chamber 27, but in cold weather it is frequently necessary to admit warm air to the mixing chamber. To permit a mixture of warm and cold 15 air suitably proportioned at all times to the temperature of the atmospheric air, I have provided means which are shown in Figs. 1 and 2, and in detail in Figs. 5, 6 and 7.

Referring first to Figs. 1 and 2, the exhaust 20 from the engine 3 issues through a pipe 41 passing thence along to the rear of the vehicle to a suitable muffler (not shown). Partially surrounding the exhaust pipe 41 is a casing 42 forming a chamber through 25 which air is drawn through the perforations shown, which air is, of course, heated by passing therethrough in contact with the heated wall of the exhaust pipe.

This chamber is in communication with 30 the inlet opening 43 (see dotted lines Figs. 2 and 6) of the hot air mixing device 44, the latter shown as cylindrical in shape and provided with a second inlet opening 45 through which ordinary atmospheric air 35 is admitted.

The ends of the cylinder 44 are closed by two caps 46 and 47, provided respectively with segmental portions 48 and 49 (see Fig. 5) adapted, when in certain rotative position, to partially or wholly close their respective openings 43 and 45. One of these caps, as 46, is provided with a bolt 50 which extends longitudinally through the cylinder 44 and through the cap at the opposite end 45 thereof, and is fitted outside the latter cap with a wing nut 51. By slackening this nut, the two caps 46 and 47 may be rotated relatively or in unison as required to obtain the desired proportionate supply of cold 50 air through the opening 45 and warm air through the opening 43, or air may be drawn through either one of these openings to the exclusion of the other if desired.

The air thus admitted to the cylinder 44 55 passes therefrom through the opening 52 and the pipe 53 (see Fig. 2) to the inlet 35 of the mixing device 7 (Fig. 3). Having then properly adjusted the cold and warm air supply the caps are clamped in position 60 by the wing nut 51.

The peripheries of the caps 46 and 47 may be milled to enable them to be easily engaged and rotated by the hand of the operator and they are also graduated as indicated at 54

(Fig. 7) to indicate to the operator the positions of the segmental extensions within the cylinder 44, and the degree of opening or closing of the inlet openings therein.

At 55 (Fig. 3) I have provided a supplemental air inlet which is controlled automatically by an opening 56 in the cylindrical throttle 31. As the latter is rotated to completely open the exit opening 38 leading to the engine showing a demand for more combustible, the supplemental air opening 55 70 will also be proportionally opened to furnish the required additional air supply. As a further means for regulating this air supply, I have provided the supplemental air supply opening 55 with a supply pipe 57 which 75 leads to a point conveniently accessible to the operator where it is provided with means such as a swing valve 58 for regulating the inlet thereto and the volume of air permitted to pass therethrough.

This invention is not restricted to the particular embodiment thereof here shown and described, but the same may be varied within wide limits without departing from the spirit and scope of the invention.

Claims.

1. The combination in a carbureter for an internal combustion engine of a fuel supply device comprising an atomizing nozzle, an air conduit opening adjacent the 95 mouth of said nozzle, means to supply air thereto in the direction of discharge, a foraminous wall above which said nozzle discharges and means to supply air through said wall to the atomized fuel.

2. The combination in a carbureter for an internal combustion engine of a fuel supply device comprising an atomizing nozzle, an air conduit opening adjacent the mouth of said nozzle, means to supply air thereto, 105 a baffle opposite said nozzle, a foraminous wall located to receive fuel from said baffle and means to supply air through the wall.

3. The combination in a carbureter for an internal combustion engine of a fuel supply 110 device comprising an atomizing nozzle, an air conduit opening adjacent the mouth of said nozzle, means to supply air thereto in the direction of discharge, a baffle of comparatively large area facing said conduit 115 and means to provide a regulated supply of air outwardly of said nozzle and conduit.

4. The combination with a variable speed internal combustion engine, of a carbureter having a mixing chamber, a throttle valve 120 between the engine and the mixing chamber adapted to vary from time to time the amount of mixture passing to the engine to control the speed thereof, said carbureter having also an atomizing nozzle with means 125 for constantly maintaining a supply of fuel at the nozzle, a casing provided with gradually converging walls about said nozzle,

means for passing through the space between said converging walls about said nozzle a substantially constant supply of air, means for passing to said mixing chamber 5 an auxiliary air supply, and valve means to regulate said auxiliary supply operating in coördination with the speed variations of the engine.

In testimony whereof, I have signed my name to this specification, in the presence 10 of two subscribing witnesses.

ANDREW L. RIKER.
